(57) **CLAIM**

The ornamental design for oxygen cannula protector, as shown and described.

DESCRIPTION

FIG. 1 is an isometric top view of a oxygen cannula protector showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an isometric top view of my design in the open position.

The broken line showing of the cannula is environmental only and forms no part of the claimed design.

1 Claim, 4 Drawing Sheets

FIG. 1

FIG. 2**FIG. 3****FIG. 4****FIG. 5**

FIG. 6

FIG. 7
